BOAT FENDER

Lawrence A. Loeb, 37 Trumbull St., New Haven, Conn.

Filed July 3, 1962, Ser. No. 70,792

Term of patent 14 years

(Cl. D71—1)

Fig. 1.

Fig. 2.

Fig. 3.

Fig.4.

Fig.5.

Fig.6.

FIG. 1 is a side elevational view of a boat fender showing my new design;

FIG. 2 is a side elevational view of the other side of the boat fender shown in FIG. 1;

FIG. 3 is an end elevational view of the boat fender shown in FIG. 1, the opposite end not shown being substantially the same in appearance;

FIG. 4 is a side elevational view of a modified form of the boat fender shown in FIG. 1;

FIG. 5 is a side elevational view of the other side of the modified boat fender shown in FIG. 4; and

FIG. 6 is an end elevational view of the modified boat fender shown in FIG. 4, the opposite end not shown being substantially the same in appearance.

This application is a continuation-in-part of applicant's application D. 65,992, filed July 20, 1961 and now abandoned.

I claim:

The ornamental design for a boat fender, as shown and described.
